CLAIM

The ornamental design for a keyed electrical connector, as shown and described.

DESCRIPTION

FIG. 1 is a rear perspective view of a keyed electrical connector, showing my new design;

FIG. 2 is a front perspective view thereof;

FIG. 3 is a top view thereof;

FIG. 4 is a side view thereof;

FIG. 5 is a bottom view thereof; and,

FIG. 6 is a front view thereof.

The broken line portion of the figure drawings is included to show unclaimed subject matter only and forms no part of the claimed design.
